(57) **CLAIM**

The ornamental design for a stove, as shown and described.

DESCRIPTION

FIG. 1 is a front, top and right side perspective view of component 1 of the stove, showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof; and

FIG. 7 is a bottom plan view thereof;

FIG. 8 is a front, top and right side perspective view of component 2 of the stove thereof;

FIG. 9 is a front view thereof;

FIG. 10 is a rear view thereof;

FIG. 11 is a left side view thereof;

FIG. 12 is a right side view thereof;

FIG. 13 is a top plan view thereof;

FIG. 14 is a bottom plan view thereof;

FIG. 15 is a front, top and right side perspective view of two components in combination status thereof; and,

FIG. 16 is a front, top and right side perspective view in use status thereof.

1 Claim, 16 Drawing Sheets
